UNITED STATES PATENT OFFICE

162,431

NECKTIE HOLDER OR SIMILAR ARTICLE

Robert W. Nelson, Lancaster, N. Y.

Application March 30, 1950, Serial No. 8,870

Term of patent 14 years

(Cl. D33—8)

To all whom it may concern:

Be it known that I, Robert W. Nelson, a citizen of the United States of America, residing at Pleasant View Drive, Lancaster, Erie County, State of New York, have invented a new, original, and ornamental Design for a Necktie Holder or Similar Article, of which the following is a specification, reference being had to the accompanying drawing, forming a part hereof.

In said drawing:

Fig. 1 is a perspective view of a necktie holder or similar article, showing my new design.

Fig. 2 is a side elevation thereof.

Fig. 3 is an end elevation thereof.

I claim:

The ornamental design for a necktie holder or similar article, as shown.

ROBERT W. NELSON.
